UNITED STATES PATENT OFFICE.

FRANK N. SPELLER, OF PITTSBURGH, PENNSYLVANIA.

APPARATUS FOR HEATING AND DEOXIDIZING WATER.

1,274,099.

Specification of Letters Patent. Patented July 30, 1918.

Application filed April 29, 1918. Serial No. 231,428.

To all whom it may concern:

Be it known that I, FRANK N. SPELLER, a citizen of the United States, and resident of Pittsburgh, in the county of Allegheny and

5 State of Pennsylvania, have invented certain new and useful Improvements in Apparatus for Heating and Deoxidizing Water, of which the following is a specification.

The present invention relates to apparatus 10 for use in removing the free oxygen and other soluble corrosive matter and in filtering heated water, and is an improvement over the apparatus disclosed in my Patent No. 1,204,602, granted November 14th, 1916.

15 One of the objects of the invention is to combine the heater and deoxidizing apparatus in one unit.

Another object is to utilize the tank which incloses the heating coils and deoxidizing 20 plates as a storage vessel for hot water.

Another object is to associate a filter with the combined heater and deoxidizer in such a manner that the deoxidized water may be cleansed of any rust or scale before entering 25 the house piping.

A still further object is the provision of apparatus having the novel features of construction shown and described and particularly pointed out in the subjoined claims.

30 Referring to the drawing forming part of the specification;

Figure 1 is a longitudinal sectional view of the apparatus with parts shown in side elevation;

35 Fig. 2 is a fragmentary plan view of one of the deoxidizing plates, and Fig. 3 is a cross section thereof.

Referring to Fig. 1 the heating unit comprises a number of return bends of pipe 4 40 the upper ends 5 of which are connected with an inlet header 6 and at their lower ends 7 with an outlet header 8. The headers 6 and 8 are connected respectively with steam inlet and outlet pipes 9 and 10.

45 The headers 6 and 8 are secured by any suitable means to the drum head 11 of the combined heating deoxidizing and storage tank 12. The heating coils 4 project into the tank and are surrounded by a skeleton

50 frame consisting of longitudinally extending bars 13, transverse bars 14 and uprights 15. Within the tank 12 are placed a plurality of superposed expanded sheet steel or iron plates 16 which may have apertures 17

55 formed therein which are surrounded by projecting ribs 18 as shown in Figs. 2 and 3.

By forming the sheet metal plates in this manner, a multiplicity of chambers are formed between the various plates thereby providing a large area of metallic surface 60 over which the water passing through the deoxidizer will come in contact. The apertures 17 furthermore permit of free passage of the water from one chamber to another. The skeleton frame formed by the bars 13, 65 14 and 15 serves to support the deoxidizing plates which are located above the heating coils 4.

In the preferred embodiment of the invention, I propose to use a filter indicated generally by the numeral 20, which comprises a cylindrical casing 21 divided into two chambers 22 and 23 by a reticulated diaphragm 24. Any suitable filtering medium such as sand or sand and gravel is contained 75 in chamber 22 and the chamber 23 forms a header through which the filtered water may freely pass. A circulating coil 25 is mounted within the chamber 22 of the filter and connected with the deoxidizing tank 12 in a 80 manner to be presently described.

A set of auxiliary heating coils 26 are shown in Fig. 1 which may be utilized instead of the circulating coil 25. In operation cold water flows through the pipe 27 85 and the normally open control valve 28 into the combined deoxidizing heating and storage tank 12, through which it slowly flows and is heated by the coils 4. During its passage through the tank, the plates 16 act 90 upon the water which rises up and removes practically all of the free oxygen from the water, thereby preventing the corrosion and destruction of the piping throughout the hot water pipe line. The heated water passes 95 out at the top of the tank through pipes 29 and 30 and part of it is shunted through the pipe 31 to the circulating coil 25 thence by a pipe 32 through the normally open valve 33 and by a pipe 34 into the bottom 100 of the tank as indicated by the arrows. The comparatively hot water taking this course induces a constant thermo-siphon circulation through the tank 12. Under normal conditions the valve 35 in the pipe 30 is open and the valve 36 is closed and this will permit the normal circulation of water from the tank 12 through pipes 29 and 30 and valve 35 into the top of the filter by way of pipe 37. The water permeates through the filtering medium in the chamber 22 and into the header 23 and thence flows up through the 105

pipe 38 which is connected at its upper end by a T 39 with the hot water supply pipe 40 which is provided with the usual control valve 41. The filter may be kept hot by means of the coil 25 above described, or an auxiliary heater 26 may be provided for this purpose and to facilitate circulation, and circulation may be further accelerated by a centrifugal pump 42 when necessary. In 10 either event the water is returned to the header 23 of the filter by way of pipes 43 and 44.

When it is desired to use the auxiliary heater 26, a valve 43^a located in the return line 43 is closed and the inlet and outlet valves 26^a and 26^b which connect the auxiliary heater with the return line 43 are opened and the water will take the course indicated by the arrows. By closing the valves 20 26^a and 26^b and opening the valve 43^a it is obvious that the auxiliary heater will be rendered inoperative. When the auxiliary heater 26 is used, it is unnecessary to provide the circulating coil 25.

If, for any reason, it may not be desired to filter the water which has been deoxidized it will be clear that by opening the valve 36, the water may flow directly to the pipe 40 and out through the system and back to the 30 tank 12 by way of an auxiliary return pipe 44 which may be provided for the purpose and which includes a control valve 45. A pipe 46 including a normally closed valve 47 is connected with the sewer so that the heating tank may be occasionally flushed out to 35 discharge any accumulation of iron oxids or other scale which may accumulate within the tank. A pipe 48 provided with a valve 49 is also provided for cleaning out the 40 circulating coil 25.

From the foregoing it will be seen that the present invention is a simplification and improvement over the apparatus disclosed in my Patent No. 1,204,602, above referred to. It saves considerable expense in building a plant of this description to combine the heating and deoxidizing elements in one structure. In building the apparatus in this way the storage tank which is utilized also 45 for the heater and deoxidizing tank only needs to be made a trifle larger than would otherwise be necessary. The heating coils occupy comparatively a small amount of space and the thin sheet metal plates, (which 50 in the drawings are shown of an exaggerated thickness), displace a very small quantity of water and therefore the storage capacity of the tank is not materially reduced by 55 their presence.

Though I have described with great particularity of detail certain embodiments of my invention, yet it is not to be understood therefrom that the invention is restricted to the embodiments described. Various modifications thereof in detail and in the ar-

rangement of the parts may be made by those skilled in the art without departure from the invention as defined in the following claims.

Deoxidizing, as used in this specification, 70 refers to the removal of the "free" or dissolved oxygen normally present in water, this free oxygen being the most active agent in promoting corrosion and water becoming inactive by the removal of its free oxygen. 75

What I claim is:—

1. A water heater including a heating unit and a plurality of thin sheet steel or iron plates for deoxidizing the water as it passes through the heater. 80

2. A water heater comprising a heating unit, a plurality of thin sheet steel or iron plates and a tank inclosing said heating unit and plates in which the water is heated, de-oxidized and stored. 85

3. A water heater comprising a heating unit, a plurality of superposed expanded sheet iron or steel plates, forming a multiplicity of passages and exposing a great area of metallic surface to act on the water passing through the tank and a single tank inclosing said heating unit and sheet metal plates. 90

4. A plant for heating, deoxidizing and filtering water including in combination a tank enclosing a heating unit and a plurality of thin sheet steel or iron plates and a filter communicating with said tank. 95

5. A plant for heating, deoxidizing and filtering water including in combination a tank inclosing a heating unit and a plurality of thin sheet steel or iron plates, a filter, an outlet pipe from said tank connected to the filter, a pipe coil within said filter connected at one end to said outlet pipe and at the other end to said tank to induce a circulation through the tank and pipe coil, outlet piping from said filter and return piping to said filter. 100

6. A plant for heating, deoxidizing and filtering water including in combination a tank inclosing a heating unit and a plurality of superposed expanded sheet steel or iron plates forming a multiplicity of passages and exposing a great area of metal surface to act on the water passing through the tank, a filter and piping connecting the filter and tank for maintaining an independent circulation therebetween. 110

7. A plant for heating, deoxidizing and filtering water including in combination a tank inclosing a heating unit and a plurality of superposed expanded sheet steel or iron plates forming a multiplicity of passages and exposing a great area of metal surface to act on the water passing through the tank, a filter and an auxiliary heater to maintain circulation and the temperature of the filter when hot water is not being drawn therefrom. 120

8. A plant for heating, deoxidizing and filtering water including in combination a tank inclosing a heating unit and a plurality of superposed expanded sheet steel or iron plates forming a multiplicity of passages and exposing a great area of metal surface to act on the water passing through the tank, a filter, piping connecting the filter and tank for maintaining an independent circulation therebetween, outlet piping from said filter, a return pipe leading to said filter, an auxiliary heater connected to said return pipe, valves for controlling the circulation of water between said return pipe and said auxiliary heater and a circulating pump 15 connected to said return pipe.

In witness whereof I have hereunto signed my name.

FRANK N. SPELLER.
